UNITED STATES PATENT OFFICE

135,400

DESIGN FOR AN INDUSTRIAL TRUCK

Truman B. Funk, Jackson, Mich., assignor to Yard-Man, Inc., Jackson, Mich., a corporation of Michigan

Application April 9, 1942, Serial No. 106,516

Term of patent 14 years

To all whom it may concern:

Be it known that I, Truman B. Funk, a citizen of the United States, residing at Jackson, in the county of Jackson, and State of Michigan, have invented a new, original, and ornamental Design for Industrial Truck, of which the following is a specification, reference being had to the accompanying drawings, forming part thereof.

Fig. 1 is a side elevational view of the industrial truck showing my new design.

Fig. 2 is a rear elevational view with the motor driving mechanism and rear wheel assembly rotated through 180° from the position shown in Fig. 1, and

Fig. 3 is a front elevational view thereof with the motor driving mechanism and rear wheel assembly rotated through 180° from the position shown in Fig. 1.

I claim:

The ornamental design for industrial truck, substantially as shown.

TRUMAN B. FUNK.
